(57) **CLAIM**

We claim the ornamental design for a vehicular power adapter, as shown and described.

DESCRIPTION

FIG. 1 is a left side view of the vehicular power adapter, according to this invention;

FIG. 2 is a top view of the vehicular power adapter;

FIG. 3 is an end view of the vehicular power adapter;

FIG. 4 is a bottom view of the vehicular power adapter;

FIG. 5 is a right side view of the vehicular power adapter; and,

FIG. 6 is a power cord end view of the vehicular power adapter.

The chain-link portions of the vehicular power adapter is for illustrative purposes only and forms no part of the claimed design.

The Cingular Logo forming part of the claimed design is a registered trademark of Cingular Wireless, LLC.
